VARIABLE VOLUME FLUID DISTRIBUTOR

Robert L. Allen, Atlanta, Ga., assignor to Georgia Tech Research Institute, Atlanta, Ga., a corporation of Georgia
Filed Dec. 19, 1957, Ser. No. 703,862
7 Claims. (Cl. 137—568)

This invention relates to a variable volume fluid distributor, and is particularly concerned with distributors for the feeding of variable volume liquid increments to individual outlets from a single source. While the invention may find admirable utility in a wide variety of mechanisms, it has been found particularly adaptable for the distribution of measured liquid fuel increments in a fuel injection system for internal combustion engines.

In the development of fuel injection systems for multiple cylinder, high speed, four cycle, internal combustion engines, many problems are encountered with respect to the distribution of individual accurately metered minute increments. In such systems, it is, of course, fundamental that the measured increments discharged must be accurate within fractions of droplets, and that such increments be delivered at such pressure and flow rate as to overcome inertia and friction in the line as well as resistance at the point of discharge. Since intimate distribution of the fuel in the combustion supporting air is an important factor in engine efficiency, jet nozzles are provided for the spray, diffusion or atomization of fuel as it is delivered. Consistently responsive engine operation requires the delivery of fuel increments to the nozzle at a discharge pressure faithfully within a range appropriate to the best operating conditions of the nozzle. Varying speed and load conditions require varying fuel increment volumes, as well as variations in the time sequence of increment injection.

Heretofore, efforts have been made to solve the problems inherent in such high speed, variable volume feed of measured increments by the simple expedient of high pressure. By the use of high pressures, it was hoped that accurately measured, varying volume, increments would be discharged at the rate required and with such force as necessary; however, where such high pressures are resorted to, other problems are introduced frequently in the nature of pounding, vapor-locks, turbulence, and pressure binds. Since the liquid fuel is substantially non-compressible, variable volumes at high pressure necessarily produce flow disturbances. Such disturbances inhibit the uniform and accurate delivery of precisely measured varying volume increments at specific time intervals and under desirable pressure conditions. The present invention provides a distributor by which the desired accurate, effective and efficient fuel distribution may be achieved without resort to high pressure. By the use of expandable chamber means, applicant's distributor may be supplied with fuel in varying volumes, at low pressure, for effective distribution in accurately measured variable volume increments within a limited pressure range and without undue fluctuations, pounding, vapor-locks or turbulence. The pressure range referred to is such as to insure prompt fluid flow in discharge lines, overcoming frictional drag and inertia, as well as providing the required pressure at the nozzle to insure the desired character of fuel atomization.

It is among the objects of the present invention to provide a novel, simple and improved fluid distributor for the incremental distribution of fluid from a single source.

A further object of the invention is to provide a distributor having accumulator means for receiving variable fluid volumes for distribution, thereby precluding excessive pressure build-up throughout the device and insuring accurate volumetric output of the fluid.

Another object of the present invention is to provide means for insuring a rapid discharge of preselected increments of fluid in such manner as to overcome inertia

2

and friction lags from the distributor to associated mechanism.

It is also an object of the present invention to provide a distributor which, which simple in construction and operation, will properly function to distribute small incremental portions of fluid, and one which while lending itself to economic manufacture is well adapted to provide a long life of faithful operation.

Other objects of the invention include that of providing novel and improved sealing arrangements for maintaining pressures within the distributor as well as insuring against loss of fluid, and to provide a mechanism which may be easily assembled and disassembled.

Numerous other objects, features and advantages of the present invention will be apparent from consideration of the following specification, taken in conjunction with the accompanying drawings, in which:

FIG. 1 is a side elevation of one embodiment of the present invention.

FIG. 2 is a front elevation of that form of the device shown in FIG. 1.

FIG. 3 is an enlarged vertical cross section taken on line 3—3 of FIG. 2.

FIG. 4 is a reduced fragmentary cross section taken on line 4—4 of FIG. 3.

FIG. 5 is an enlarged detail cross sectional view illustrating one of the accumulators in partially retracted position.

In that form of the invention here shown by way of example, the distributor structure comprises a body 10 of octagonal configuration, the eight peripheral faces 11 of which are recessed as at 12 to receive therein the bosses 14 of individual increment fluid outlet blocks 15. Each block 15 defines an elbow fluid discharge duct 16. The outer end of each duct 16 receives fluid distribution tube 17 while the inner end of each communicates with one of eight individual radial outlet ports 18 in the body 10. The inner ends of the outlet ports 18 are in communication with the associated incremental fluid passages 19. Suitable O rings 20 are applied as required.

One face of the body, here shown in FIG. 3 as on the right hand side, is formed with an annular marginal offset 30 adapted to receive an annular shoulder 31 of a chamber housing 32. The housing 32 with the body 10 defines a fuel chamber 33. Within the chamber 33 there is mounted a flow control member in the form of a rotary distributor disc 34 which bears against the outer right hand face of the body 10 under inlet fluid pressure and yieldable spring tension. The disc 34 is provided with a single distributor port 35, here shown as elongate and of arcuate form, its center of curvature coinciding with the center of rotation of the disc 34. The length of the port 35 is less than the spacing between any two adjacent inlet ports of the passages 19, thus precluding any possibility of simultaneous registration of port 35 with more than one port 19. The disc 34 sealingly engages the right face of the body 10 to preclude the flow of fluid from the chamber 33 to the successive ducts except at such time as registration of the port 35 occurs.

In the rotation of the disc 34 to successively register its port 35 with the individual passages 19, there is of necessity an interruption of uniform fluid flow. As the disc port moves from one passage 19 to the next, fluid discharge is terminated, although fluid supply may be uniform. These discharge cut-offs are abrupt, rapid and positive, and in the absence of yieldable compensating means for receiving fluid between the discharge intervals, such as one or more accumulators as hereinafter referred to, pressure build-up vibration and pounding will result in damage or the detriment of accuracy, efficiency and stability of operating characteristics.

The disc 34 is mounted for rotation by a drive shaft

40 through means of a transverse key 41 seated within a transverse slot 42 at the inner end of the shaft 40. The key 41 is also received within a transverse recess 43 in the outer face of the disc 34. For urging the disc toward sealing engagement with the face of body 10, a counterbore 44 in the shaft 40 is provided with a spring 45 which encircles a stud 46 of the key 41 and bears against the key to exert an inward pressure of the disc 34 against the body. The outer face of the disc is subjected to the inlet fuel pressure which assists in producing a sealing pressure without undue friction or galling.

Fluid is supplied to the distributor inlet chamber 33 through port 50 in the housing 32 by supply pipe 51. Since the maintenance of pressure within a predetermined low range is essential to proper incremental distribution by the rotation of the disc despite volume changes, pressure responsive expansible chamber means are furnished. In the present construction, one such means comprises an accumulator communicating with the inlet chamber 33. As here shown, this accumulator includes a cup-shaped piston plunger 52 invertedly positioned within an accumulator piston bore 53 formed in the housing 32 and here arranged diametrically opposite the inlet port 50. The chamber 53 communicates with the chamber 33 by an accumulator port 54. The piston 52 is normally urged inwardly in the bore 53 toward the port 54 by coil spring 55 confined by cap 56. The cap 56 is secured within a counterbore 57 encircling the piston bore 53. At the inner end of the counterbore 57, a sealing O-ring 58 is provided to preclude leakage of fluid past the outer walls of the piston 52. By this arrangement, it will be seen that with the spring adequately chosen to conform to the desired pressure within the chamber 33 variable fluid volume will cause the piston 52 to be moved outwardly in its cylinder to compress the spring 55, thus maintaining said predetermined pressure throughout varying volumes. The accumulator provides for a reception of fluid exceeding the capacity of chamber 33, thus increased fluid supply will not cause an increase of pressure beyond a prescribed range, the spring pressure on the accumulator piston determining the optimum of such range.

Under certain circumstances and in certain equipment, it may well be that additional accumulator means could be profitably employed to preclude excessive pressure and to effect the adequate delivery of fluid and/or to insure the rapid passage of fluid despite friction losses and inertia of liquid in the delivery tubes 17. Where the fluid is to be discharged through injection nozzles in which spring restrained orifice closures are employed, some modifying effect on fluid flow, vibration and pressure may be achieved. However, in the absence of an established relationship between a primary accumulator pressure and nozzle flow resistance, or where other factors of pressure, flow, volume and cut-off enter, individual discharge line accumulators may be advisable. Therefore, in the present form of the invention each duct 19 is provided with an individual accumulator here shown as similar in form to the accumulator associated with the inlet chamber 33. For this purpose, each duct 19 extends transversely through the body 10 outward to the individual accumulator chamber 60 in which cup-like accumulator pistons 61 are mounted for reciprocation against the pressure of the springs 62. A cap 63 is provided for each piston 61 to retain its spring 62 in position. O-rings 64 are mounted in the counterbores 65 which receive the inner ends of the caps. For retaining all of the caps in assembled relation there is provided a spider 70, the eight terminal finger ends 71 of which rest against the eight outer faces 72 of the caps. The head 73 of a bolt 74 retains the spider in position, adequately spaced by an intervening cylindrical spacer 75. As hereinbefore mentioned, successful operation of the device has shown the single accumulator of housing 32 to be adequate; however, either or both of the accumulator arrangements may be used.

From the foregoing it will be seen that as fluid is supplied by the pipe 51 through port 50 to the supply chamber 33, such fluid will be subjected to the action of the accumulator spring 55 to establish and maintain a predetermined pressure. Such fluid will urge the piston outwardly against the spring to maintain such pressure despite possible fluctuations of inlet pressure or changes in the rate of flow of fluid supplied. Thus the accumulator will permit variations in fluid supply without substantial pressure variation, so that the engine may be supplied by various increment volumes without change in fluid pressure. As the disc 34 is rotated, the port 35 will successively register with the ports of the duct 19 to successively admit an incremental pulse of fluid from the chamber 33 to the successive ducts 19. It will, of course, be noted that the outer free face of the disc 34 is subjected to the substantially uniform pressure of the fluid in chamber 33, hence such pressure will assist spring 45 in sealingly retaining the disc over the ports 19. Such pressure, however, being limited by the accumulator will not bind or gall the disc. As the fluid is received by the ducts 19, the individual accumulators 60 to 68 will provide for a maintenance of the pressure at which the fluid is delivered and for an appropriate incremental supply to each tube 17.

It will be noted that in the movement of the disc aperture 35 between ports 19, a positive termination of discharge flow is abruptly effected. Since the fluid supply can rarely if ever be so regulated as to conform with any such rapid and positive pulsations of discharge, excessive pressures of disasterous magnitude could be built up in the absence of compensating means in the nature of the present accumulator for receiving and storing the marginal fluid delivered during the interim between fluid discharges. Not only does the accumulator receive the fluid volume supplied between incremental discharges, which volume varies as the engine demand for fuel varies, but such reception is under a sustained pressure operable to deliver such received fluid at the prescribed pressure upon the advent of the next discharge phase. Thus the present structure implements a new concept in high speed, low pressure, incremental fluid delivery, a substantially constant pressure within a predetermined range being achieved by the periodic storage of overlapping supply increments under controlled pressure conditions between the discharge intervals.

It will be noted that the structure and arrangement is simple, efficient, and effective, well designed to meet the demands of economic manufacture, formed to withstand the speeds appropriate for fuel injection systems, and which may be readily disassembled and reassembled for maintenance, service and cleaning or repairs. In the practice of the invention it will be understood that numerous changes, modifications and the full use of equivalents may be resorted to without departure from the spirit or scope of the invention as defined in the appended claims.

I claim:

1. A fluid distributor for the delivery of a plurality of separate successive pulses of fluid increments to separate discharge lines including means defining a fluid chamber, a fluid inlet to said chamber, a rotatable disc defining a single fluid outlet from said chamber, a plurality of individual fluid outlet ports successively registerable with the fluid outlet of said disc, and pressure responsive means for maintaining substantially uniform pressure of fluid discharged through said individual fluid outlet ports, said pressure responsive means including individual accumulators associated with each individual outlet port and biased to maintain substantially uniform pressure above a predetermined minimum and for discharging the accumulated fluid prior to the delivery thereto of its next increment.

2. A fluid distributor for the delivery of a plurality of separate successive pulses of fluid increments to separate discharge lines including a fluid inlet, a plurality of fluid

outlets communicating with separate discharge lines, a rotatable disc defining a single fluid passage successively registerable with said fluid outlets, and pressure responsive means for maintaining substantially uniform fluid pressure in said distributor, said pressure responsive means including a single expandable chamber accumulator constantly communicating with said inlet, and individual expandable chamber accumulators directly communicating with said individual outlets and biased to maintain substantially uniform pressure above a predetermined minimum and for discharging the accumulated fluid prior to the delivery thereto of its next increment.

3. A distributor for the fuel injection system of a multi-cylinder internal combustion engine wherein variable volumes of incremental pulses of fuel are injected to the cylinders of the engine, including a body, a circular series of individual fuel increment outlet ports defined by said body, a housing cooperating with said body to form a fluid chamber, a fuel inlet for said chamber, a rotatable disc defining a fuel outlet from said chamber, the axis of rotation of said disc being concentric with the axis of said circular series of individual fuel increment outlet ports, said disc defined outlet being elongate and of a length less than the spacing between adjacent fuel increment outlets in said circular series, and means for urging said disc toward said body, together with means for maintaining uniform fluid pressure in said distributor during discharge of said variable volumes, said means including an expandable chamber accumulator constantly communicating with said chamber and a plurality of expandable chamber accumulators communicating respectively with said individual outlet ports, said accumulator in communication with said chamber being biased to maintain substantially uniform pressure above a predetermined minimum between the delivery of one such increment and the next and for discharging the accumulated fluid during the delivery of said next increment.

4. A fluid distributor periodically delivering separate increments of fluid from a single fluid supply which may vary independently of variations of the time between the delivery of one such increment and the next, said distributor defining a fluid supply chamber together with a fluid supply duct and a fluid discharge duct, means movable in said chamber to periodically deliver fluid increments from said chamber to said discharge duct, and means in constant communication with said chamber for accommodating variable volumes of fluid at uniform pressure within said chamber, said means including a pressure responsive variable displacement accumulator biased to maintain substantially uniform pressure above a selected minimum, below which said accumulator is inoperative to receive fluid, between the delivery of one such increment and the next and for discharging the accumulated fluid during the delivery of said next increment.

5. A fluid distributor periodically delivering separate increments of fluid from a fluid supply which may vary independently of variations of the time between the delivery of one such increment and the next, said distributor defining a fluid supply chamber, a fluid inlet to said chamber and a fluid outlet from said chamber, means

movable in said chamber to periodically deliver increments of fluid from said chamber to said fluid outlet, and means for varying the effective capacity of said chamber, said last mentioned means including a pressure responsive fluid accumulator in constant communication with said inlet and biased to maintain substantially uniform pressure above a selected minimum, below which said accumulator is inoperative to receive fluid, from between the delivery of one such increment and the next and for discharging the accumulated fluid during the delivery of said next increment.

6. In a distributor having a chamber, means for discharging liquid from said chamber as spaced intervals, means for constantly delivering liquid to said chamber in quantity which may vary independently of variations in the time between such intervals, and yieldable means for accommodating the supply of liquid between said intervals of discharge so as to maintain the fluid pressure in said chamber substantially constant above a selected minimum, below which said accumulator is inoperative to receive fluid, between the discharge at one interval and the next and for discharging the accommodated liquid during the discharge at said next interval.

7. A fluid distributor for the timed delivery of fluid increments comprising a supply chamber for fluid, a distributor member having a surface with a plurality of annularly disposed and circumferentially spaced delivery ports, a distributor plate between said supply chamber and said surface and having a release port to successively register with said delivery ports upon the rotation of said plate, said release port being of a maximum circumferential dimension to prevent simultaneous opening of any two adjacent ports, means for delivering fluid to said supply chamber in quantity which may vary independently of the speed of rotation of said distributor plate, an accumulator chamber having a movable wall, and biasing means for urging said wall in a direction to reduce the size of said accumulator chamber, said wall and said biasing means having a frequency response sufficiently great to follow pressure changes in said supply chamber for maintaining substantially uniform pressure above a selected minimum pressure, below which said accumulator is inoperative to receive fluid, between the registering of said release port with any one of said delivery ports and the next adjacent port and for reducing the size of said chamber to a predetermined minimum upon registration of said release port with said next adjacent port.
